UNITED STATES PATENT OFFICE.

ALBERT O. SCHRAMM, OF LOS ANGELES, CALIFORNIA, ASSIGNOR TO SCHRAMM MANUFACTURING COMPANY, OF ST. LOUIS, MISSOURI, A CORPORATION OF MISSOURI.

APPARATUS FOR STRETCHING LAUNDERED ARTICLES FOR DRYING.

Application filed October 17, 1921. Serial No. 508,240.

To all whom it may concern:

Be it known that I, ALBERT O. SCHRAMM, a citizen of the United States, residing at Los Angeles, in the county of Los Angeles and State of California, have invented new and useful Improvements in Apparatus for Stretching Laundered Articles for Drying, of which the following is a specification.

- 10 This invention relates to apparatus for stretching laundered articles for drying and it has for its object to provide improved apparatus of the general nature stated whereby such articles as lace curtains, bed 15 spreads and like articles may be properly held in stretched condition during the drying thereof to restore the original outlines thereof and cause the same to be evenly and smoothly dried.
- 20 The present invention constitutes an improvement upon or departure from inventions of this general nature disclosed and claimed in other applications for Letters Patent filed by me March 1, 1920, Serial 25 Number 362,421, and December 21, 1920, Serial Number 432,992, both for improvements in apparatus for stretching laundered articles for drying.

In accordance with the invention and in 30 the preferred practice thereof, I provide a stretcher frame adapted to receive a plurality of washed articles at each face thereof, independently adjustable means for holding each article being preferably provided.

35 In certain aspects, the invention contemplates the provision of novel stretcher apparatus details, such as frame and mounting structure, positive means of adjustment for both ends of an adjustable frame member, 40 means for securing such member in any of its positions of adjustment, and further like novel details of construction and organization, as will hereinafter be set forth.

A further object of the invention is to 45 produce stretching apparatus for flat washed articles, which will be relatively simple and inexpensive in construction and organization, when its advantages, such as positive and speedy adjustment of washed articles thereto, durability, freedom from liability

to get out of order or repair, and general superiority in service are considered.

With the above and other objects in view, the invention consists in the novel and useful provision, formation, combination, association and relative arrangement of parts, members and features, all as hereinafter described, shown in the drawings, and finally pointed out in claims.

In the drawings:

Fig. 1 is a fragmentary vertical face view of stretching apparatus constructed and organized to embody the invention;

Fig. 2 is a fragmentary enlarged inside face view of one of the movable frame members showing portions of means for causing the simultaneous advance of both ends of such member as well as showing a means for holding or locking the same in any of its positions of adjustment;

Fig. 3 is an enlarged sectional detail view taken on the line x^3-x^3 , Fig. 2, and looking in the direction of the appended arrows;

Fig. 4 is an enlarged fragmentary view of a portion of the showing of the locking or securing means shown in Fig. 2;

Fig. 5 is a view similar to Fig. 3 but showing the locking or securing means in inoperative position to permit adjustment of the adjustable frame member;

Fig. 6 is a fragmentary inside face view of the fixed longitudinal main frame member illustrating adjustment means features; the view being taken looking in the direction of the arrow 6, Fig. 1;

Fig. 7 is a fragmentary transverse sectional view taken on the line x^7-x^7 , Fig. 1, and looking in the direction of the appended arrows;

Fig. 8 is a fragmentary view of one of the faces of the fixed longitudinal frame member, the view being taken looking in the direction of the arrow 8 near Fig. 7;

Fig. 9 is a fragmentary front face view of one of the adjustable longitudinally ranging frame members shown in Fig. 1;

Fig. 10 is an end view showing the preferred construction of the member shown in Fig. 9;

Fig. 11 is an edge view of the member

shown in detail in Figs. 9 and 10, the view being taken looking in the direction of the arrow 11, Fig. 1;

Fig. 12 is an end view of a spring clip or adjustment means;

Fig. 13 is a side elevation of the clip shown in Fig. 12;

Fig. 14 is a sectional detail view taken on the line $x^{14}-x^{14}$, Fig. 1, and looking in the direction of the appended arrows, parts being omitted for clearness of illustration;

Fig. 15 is an enlarged view of a portion of the showing in Fig. 1, showing details of a transverse adjustable member;

Fig. 16 is an enlarged front face view of one of the transverse adjustable frame members;

Fig. 17 is a fragmentary isometric view of one end of one of the end main frame members showing one mode of application of the removable extensions preferably employed in connection with the frame;

Fig. 18 is a fragmentary face view of one end of a modified form of end frame member showing a hinged extension provided thereon;

Fig. 19 is an end view of the showing in Fig. 18, and looking in the direction of the arrow 19 near Fig. 18;

Fig. 20 is a partial sectional detail view taken on the line $x^{20}-x^{20}$, Fig. 1, and looking in the direction of the appended arrows;

Fig. 21 is a view similar to Fig. 4, but illustrating the construction of a modified form of locking or securing means;

Fig. 22 is a transverse sectional detail view of a modified form of adjustable frame member; and

Fig. 23 is a bottom plan view of the member shown in Fig. 22, the same being shown in this figure in detached position.

Referring with particularity to the drawings, in the embodiment of the invention shown in Figs. 1, 2, 3, 4, 5, 6, 7, 8, 9, 10, 11, 12, 13, 14, 15, 16, 17 and 20 thereof, A designates a stretcher frame, B designates means for carrying the frame A, C designates a track for the carrying means B, and D designates guide means for the lower portion of the carrying means B.

The frame A is shown as comprising a longitudinal side edge member 24 having end members 25 and 26 fixed thereto and extending therefrom at right angles, an intermediate member 27 fixed thereto at one of its ends and extending therefrom in parallel relation to the end members 25 and 26, adjustable members 28 and 29 extending from the end member 25 to the intermediate member 27, and adjustable members 30 and 31 extending from the end member 26 to the intermediate member 27. The outward or front faces, at both faces of the frame A, of the members 24, 25, 26, 28, 29, 30 and 31, preferably have strips of carding cloth 32

applied thereto, the points of the carding cloth on each strip being outwardly directed; such carding cloth comprises a body portion and a plurality of obliquely directed points constituting article-engaging means projecting therefrom, all as described in connection with the frames described in the hereinbefore mentioned applications. The intermediate member 27 may be employed without such carding cloth, as I preferably provide means such as a and a' in connection with the frame A to hold the inner edges of articles placed on the frame for drying.

The means a is shown as a rod 33 having a reduced end 33^a at its one end, such reduced end being received in one of a series of orifices or apertures 34' provided in the upstanding flange 34" of an angle member 34 one of which is provided at each of the two faces of the frame on the member 24. The opposite end of the rod is received between two upstanding opposed spring tongues 35' of a device 35 adapted to be adjustably applied to a member 28, 29, 30 or 31 as by inserting the foot 35" which has a head thereon through any one of a series of elliptical apertures 36; each member 28, 29, 30 and 31 is provided with such a series of elliptical apertures in a raised strip spaced slightly above the main body 34 of the respective member; such main body, in each case, may be conveniently formed from a suitable length of channel section metal which will provide the necessary strength with minimum weight. The device 35 is turned a quarter turn after the foot thereof has been passed through the respective elliptical aperture, so to hold the respective device or spring clip in the proper position of adjustment along the respective member to correspond with the aperture in which the reduced end of the rod is placed. The rod may be passed through the "casing" of a lace curtain or like object, so to hold one end or edge thereof, the remaining edges being held by the carding cloth points.

The means a' is shown as a member 37 of channel cross section having a strip of carding cloth applied thereto, and as having a pair of projections 37^a at its one end, and as having a slidably adjustment device 38 at or near its other end. An embodiment of the means a' may be employed for holding the inner edge of an article to be stretched which has no "casing" to receive the rod 33. The points or projections 37^a may be entered into any suitable pair of the apertures 34', the adjustable device 38 moved along the channel member to register with the apertures 36 of a member 28, 29, 30 or 31, a laterally extending tongue 38^a of the device 38 being passed through one of the apertures 36 and an opposite lateral projection 38^b of the device 38 may be buttoned to the respective member by passing a de-

- vice like or similar to the spring clip device 35 the foot of which is passed through an elliptical aperture 38^c in the projection 38^b and through a registering aperture 36.
- 5 Each of the members 28, 29, 30 and 31, may comprise in addition to the parts hereinbefore described, means *b* for causing the simultaneous advance of both ends of the respective member, and releasable means *b'*
- 10 for normally holding such member in any of its positions of adjustment. The means *b* may comprise a shaft 39 journaled as at 40 in the channel of the respective member, a pinion or gear 41 secured to each end of the shaft 39, and racks 42 having teeth 43^a with which the corresponding gears mesh, the racks 42 being mounted at the corresponding inner faces of the parallel members 25, 26 and 27. Each releasable locking
- 15 means *b'* may comprise an intermediate gear 43 on the shaft 39, a fixed rack 44 mounted as at 44' in the channel of the respective member, and a cam member 45 hinged at one end as at 45^a to the respective member
- 20 and having an elongated aperture 45^b through which the shaft 39 passes, a contractible spring 46 secured at its one end 46^a to the member and secured at its other end to the outer end of the cam member
- 25 45 so to normally hold the shaft with the gear 43 in mesh with the rack 44; for releasing the shaft from its locking means, I preferably provide a pair of cords 47 each having one end secured to the end of the cam
- 30 member as at 47^a and having its opposite end secured to a releasing lever 48, one end of which is pivotally mounted as at 48^a in each end of the respective member. The spring 46 causes the cam member to normally deflect or bend the shaft 39 so to hold the locking gear and rack in mesh; when, however, an operator grasps one or both of the two levers 48 and moves the same outwardly to draw the cam member out of contact with
- 35 the shaft 39, the shaft may return, due to its inherent springiness, to its true axis of rotation, the locking gear being then out of mesh with its rack, and the respective member 28, 29, 30 and 31 moved to and fro with
- 40 respect to the fixed side edge member 24 of the frame A, the member being moved being always maintained in parallel relation to the side edge member 24 due to the simultaneous advance of both ends of the moving
- 45 member by the shaft, gear and rack devices. Upon release of the lever or levers the shaft is immediately moved into its normally locked position by the cam member and
- 50 spring mechanism.
- 55 Means for holding the frame in horizontal or article-receiving position, with either of the two faces thereof upwardly presented, may comprise a chain 50 having its one end secured to the carrier frame as at 50^a and having its other end secured to the mem-

ber 25 of the frame A, as at 50^b. Substitute means, to be used under certain conditions of frame adjustment, may comprise a rod 51 having its one end loosely pivotally mounted on the carrier frame as at 51^a, and having its other end provided with an in-turned finger 52^b adapted to be inserted in a suitable aperture 53 in the side member 26 of the frame A.

The frame A is shown as rotatably 75 mounted in its carrier by means of a shaft 54 passed through suitable apertures at 54^a in the frame members 25 and 26 and having its ends 54^b rotatably journaled in the carrier or carrying means B.

The carrier B is shown as comprising a framework having an upper horizontal member 55, depending end members 56 and 57 secured thereto, and rollers 58 mounted upon the member 55 and adapted to cooperate 85 with a track element. Journal bearings are provided in the carrier frame at 59 and 60, to receive the journals 54^b at the ends of the shaft 54 of the frame A.

The frame members 25, 26 and 27 may be formed with removable extensions 25^a, 26^a and 27^a, respectively, one mode of forming such extensions being illustrated in detail in Fig. 17. This figure also well illustrates the preferred formation and arrangement of the two-faced racks 42 which are applied to the inner edges of the members 25 and 26 and to the edges 27^a and 27^b of the intermediate member 27. The extensions each 90 preferably comprise a suitable length of channel section metal, or of other cross section to match the corresponding member, the extension 25^a of the member 25 being shown in this figure as having an inside joining member 25' riveted thereto and projecting therefrom into the interior of the member 25 at the end thereof, so forming a telescopic joint. The extensions may all 95 be removed when the frame is to be used for stretching articles of ordinary size and may be readily replaced when large articles are to be placed on the frame; the extensions are provided with extensions of the racks 42 so that the adjustable members 28, 29, 100 30 and 31, or any of the same may be moved out upon such extensions in the manner in which such members are moved upon the parallel frame members supporting such extensions.

In Fig. 20 one end of the member 28 is shown, the member being shown as cut away at 28' to accommodate and clear the respective rack 42, and as provided with a guide member 28'' underlying the respective rack 42, the member being guided by the rack-bearing channel member which is shown as applied in back to back relation to the main channel member to which the rack-bearing channel member is affixed. As all of the 115 members 28, 29, 30 and 31 may be formed at

both of their ends similarly to the formation illustrated in this figure, and as the racks 42 are provided at each face of the frame, and so in each of the four article-receiving sections thereof, such members may be independently adjusted, and four articles, each of which may be of a different size may be secured to the frame at one "loading" thereof; or four articles of the same size 10 may be similarly secured to the frame for drying at the same time.

In Figs. 18 and 19, I have illustrated how a modified form of extension for the members 25, 26 and 27 of the frame may be constructed. In this figure a main member is indicated by 61 and an extension 62 is hinged thereto as at 63; the member 61 is cut away at 61' to accommodate the hinged extension 62 when the same is in retracted 20 position.

In Fig. 21, I have shown a slightly modified form of locking means for the shafts 39. The usual gear 43 is provided upon a shaft 39, but instead of moving or deflecting the shaft itself, a movable lock bolt 43' is normally urged into the teeth of the gear 43 by a compression spring 43^a accommodated in a housing 43^b in which the bolt 43' is slidably mounted; the housing is secured to a member 28, 29, 30 or 31, and is slotted as at 43^c to accommodate the movement of a pin 43^d which projects therethrough from the bolt 43', and a pair of wires or cords 43^e pass over pulleys 43^f, each to one of the control levers. Upon movement of the levers to pull the bolt out of engagement with its gear, through the cords 43^e, the corresponding frame member may be moved to the desired position of adjustment.

In Figs. 22 and 23, I have shown a modified form of adjustable frame member or article holding means, to be employed in substitution for either the means *a* or the means *a'* hereinbefore described. In this 45 form of the invention a channel member 63' is provided with a strip of carding cloth not shown in the channel thereof, and with spring clips at 65 and 66. Two spring clips 65 are shown as applied to the channel member 63 at its under side or face. These 50 spring clips are each attached to the member 63 only at their inner ends, the outwardly directed free ends thereof being bent upwardly to form a detent 65^a. The spring 55 clips 66 are shown as two in number and as each having one end 66^a attached to the under side of a slideable member 66^b formed to slide upon the channel member 63 and as each having its free end formed with a 60 detent 66^c. The frame members 67 and 68 to which the channel member 63 is to be applied are shown as of angular formation, one 65 web of each such member 67 and 68 being provided with a series of spring-clip-receiving apertures 67' and 68', respectively. The

free ends of the clips are passed through the respective apertures 67' and 68' and the channel member 63 is held in place by the springs and the detents thereof clutching the webs of the frame members 67 and 68 upon which 70 the channel member 63 lies.

The track C is shown as a rail suitably supported above the carrier means B and adapted to receive the rollers of the carrier frame, and such track may lead from a suitable loading or unloading station to the interior of a dry kiln or other suitable place for the drying of the washed articles on the frame A.

The guide means D may comprise a floor 80 rail below the rail C, the lower end of the carrier frame being adapted for co-action therewith, so providing for stability, especially during the frame loading and unloading operations when the frame A is first 85 moved so as to present one face upwardly and next to present the opposite face upwardly and then to vertical position in which position it may be held by a suitable latch *d* acting between the carrier frame and the 90 frame A. The chain permits movement of the frame to these positions and checks excessive movement when the frame is moved to present either face upwardly, and so may constitute means for holding the frame A in 95 either of its article-receiving positions. The latch device *d* constitutes means for holding the frame in vertical position in its carrier.

Having thus disclosed my invention, I claim and desire to secure by Letters 100 Patent:

1. A device of the character described, comprising a pair of spaced end members, a rack in connection with the inner side of each of said end members, a rigid side member in connection with said end members, a movable side member, a rotary shaft supported by said movable side member, pinions on said shaft meshing with said racks, a locking element on said movable member, a part on said shaft to engage said locking element, and means carried by said movable side member for bending said shaft against rotation independently of said pinions.

2. A stretcher frame of the character described, comprising a pair of spaced end members, a rigid side member in connection with said end members, a rack rigid with each of said end members, a movable side member, a shaft supported by said movable side member, pinions on said shaft meshing with said racks, a rack rigid with said movable side member, a pinion rigid on said shaft for engagement with said last named rack and means for bending said shaft to engage said last named pinion with said rigid rack.

3. A stretcher frame comprising a pair of spaced fabric engaging end members, a fabric engaging side member rigid with

- said end members, a rack rigid with each of said end members, a pair of racks rigid with said side member and extending parallel with said first named racks, a pair of movable fabric engaging side members movable into and out of alinement with each other, shafts supported by said movable side members, pinions on said shafts meshing respectively with said first named and said second named racks, means for locking said shafts against rotation, an additional fabric engaging member connected with said side member and with one of said movable members, and means for attaching an edge of a fabric to each of said members.
4. A stretcher frame of the character described, comprising end members, a side member rigidly connecting said end members, a rack rigid with the inner side of each of said end members, a channel member, a shaft rotative in the channel of said channel member, pinions on said shaft meshing with said racks, an additional pinion on said shaft, a device wholly supported by said channel member engageable with said additional pinion to lock said shaft against rotation, and means supported by said channel member independently of said device for releasing said device to permit 30 said shaft to rotate.
5. A stretcher frame of the character described, comprising a fabric engaging end member, a rack rigid with said end member, a fabric engaging side member extending at right angles from said end member, a rack extending from said side member parallel with said first named rack, a fabric engaging channel member parallel with said side member, a shaft rotative in said channel member, pinions on said shaft meshing with said racks, an additional pinion on said shaft, a device supported by said channel member engaging said pinion to lock said shaft against rotation, a lever supported by said channel member independently of said device controlling engagement of said device and said pinion, an additional fabric engaging member connected with said side member and with said channel member parallel with said end member, and means in connection with each of said members for engaging a fabric.

In testimony whereof, I have signed my name to this specification.

ALBERT O. SCHRAMM.
